UNITED STATES PATENT OFFICE.

WILLIAM HENDERSON, OF NEW YORK, N. Y.

METALLIC GLAZING.

Application filed May 13, 1921. Serial No. 469,256.

To all whom it may concern:

Be it known that I, WILLIAM HENDERSON, a citizen of Great Britain, resident in the city, county, and State of New York, have 5 invented certain new and useful Improvements in Metallic Glazing, of which the following is a specification, reference being had to the accompanying drawings, illustrating particular embodiments of my invention.

This invention relates to window glazing, such as is sometimes referred to as "leaded" window panes, as for Gothic windows, and generally to glazing in which a window 15 pane is made up of a number of separate pieces of glass or in which the pane is subdivided by ledges or glazing bars. More particularly this invention relates to the glazing bars or ribs or ledges which subdivide the pieces of glass which are secured together to make up the complete window pane.

In building up the pane from a number of pieces it is an advantage and economy 25 in work to have the glazing bars properly hold the pieces in position, and this invention provides glazing bars to most effectively serve this purpose and at the same time effectively provide for holding the 30 pieces in position and permit their being permanently secured in the completed frame and providing for the required airtight joints. Among the further objects of the invention are the provision of features 35 of construction which permit the removal of a broken piece of glass and the replacement of a pane or a section of a pane without permanently marring or breaking the glazing bar, and accomplishing this repair 40 of a window quickly and economically.

In particular forms certain features of my invention are specially adapted to provide a frame that will fit the sash, with or without the sash top, providing a perfect 45 joint with the sash, with concealed attaching means readily removable in emergency without destroying the parts or permanently marring them.

Particular embodiments of my invention 50 are shown in the accompanying drawings in which—

Figure 1 is an elevation of a window sash with a Gothic divided pane.

Figure 2 is a cross-section of the glazing

bar on line 2—2 of Figure 1, on an enlarged 55 scale.

Figure 3 is a cross-section of the sash frame and a side glazing bar on line 3—3 of Figure 1, on an enlarged scale.

Figure 4 is a cross-sectional view of a 60 sash side frame similar to Figure 3, but modified to eliminate the necessity of an additional stop member on the sash or window frame.

Figure 5 is a cross-section of a modified 65 form of glazing bar adapted to be used between adjacent pieces of the pane.

Figure 6 is a fragmentary portion of a glazing bar in side elevation.

Figure 7 is a cross-section of the bar 70 shown in Figure 6, indicating in dotted lines different positions of the pliable, securing ledges.

The window "A" has the sash frame B and the pane sections or pieces a, a supported by the glazing bars C. The sash frame member B may be formed as shown in Fig. 3 and is preferably a drawn piece of zinc or copper or other metals or alloys, such that standard sections may be formed 80 with economy, and with stock construction the required lengths can be cut with which to make up any size of sash. Likewise, the glazing bar used for the interior area of the pane can readily be drawn in the sectional form shown in Fig. 2 of zinc or copper or other material, as desired, and economically produced in lengths which can be cut and bent to the required size and curvature.

In the sectional views the rib D on the double bar and the rib D' on the side sash frame bar are formed as a stiff rib member to give the glazing bar a rigid and permanent form on one side of the pane. The 95 sheet metal forming this rib continues in a bend E and a reverse bend section F forming a fixed ledge against which the rim of the glass rests. The sheet metal continues with a bend from this ledge F to a reverse bend 100 section G in the forms shown of sash sides, providing a pocket between the ledge F and leg G to fit the edge of the glass of the required thickness. As the leg G constitutes the edge of the sheet metal strip, it is pliable and may be bent as shown at G', permitting the insertion of the piece of the 105 pane of glass as in the manner indicated in

dotted lines in Fig. 3, and after insertion of the glass this pliable edge is bent down by hand and smoothed down by tool to a position firmly holding the glass against the ledge F, and thereafter the corner formed between the pliable leg and the adjacent frame or other parts is filled with putty to provide a finished crevice, air-tight, and closing the gap to prevent an accumulation 5 of dust and dirt and give the desired finish to the glazing. This glazing bar, which is sometimes called a "glazing came", has the sheet metal from the rib D' bent into the loop H to form a rib providing lateral stiffness and also a ridge adapted to engage the window frame, and the same integral sheet metal is further bent to form a leg J, providing thereby a face to accommodate the window sash stop K' which fits into the 10 corner of the sash moulding K and into which brads such as k can be driven to hold both the came or bar and the stop rigidly secured to the moulding of the window frame or sash, as desired. The sheet metal edge 15 beyond the leg J may be turned, as shown, at j to form a finished roll or beading, thereby stiffening the edge to preserve its form and finish, and providing an overchanging crevice to assist in holding the putty finish. 20 In the intermediate comes or bars, the form shown in Fig. 2 is drawn of sheet metal with the ridge D and the two ledges F' and F'', the metal of the latter being bent beyond to form the pliable ledge G to clamp 25 the opposite side of the rim of the glass. The metal from the ledge F' is bent at right angles and extended to and bent double to from the rib L and the return bend l is again bent at right angles so that the edge 30 of the sheet forms the pliable ledge M, which is complementary to the ledge F', to form the pocket in which the adjacent glass rim is held. Both pliable rims or ledges G and M being formed as the two 35 edges of the metallic strip constituting a glazing bar and having no stiffening crimp or bend, are pliable so that they may be bent out of position sufficiently to permit the insertion of the edge of the glass section, 40 without causing any distortion in the abutting or fixed ledges F', F'' or the rib portions D or L. After the glass has been inserted the pliable edges or ledges G and M are bent down and peened or smoothed down 45 by means of any convenient tool, forming a secure hold for the edge of the glass, and then the corners formed by them and the sides of the rib L suitably accommodate and hold the putty finish, as may be desired, with an assured uniformity in completing the glazing operation. 50

In the side bar member shown in modified form in Fig. 4, the leg or face J is bent to form the rib j' with a right-angled bend 55 doubled back to form a rib N, thus provid-

ing a stiff inside face adapted to fit into the mortice in the corner of the sash or window frame without the necessity of an additional stop. By this modification the strip constituting the came or bar has one edge 70 concealed in the finished structure while the other edge is on the member G, thereby providing the pliable ledge adapted to be bent out and in for the purposes of repair and replacement of broken pieces of the 75 pane.

A modified form shown in Fig. 5, has the rib D'' in modified form with the desired stiffness but with symmetrical return bend sections F''', the sheet metal then being bent 80 at right angles to form the pocket for the rim of the glass and symmetrically bent in opposite directions in a close fold O on either side and continuing in parallel sections P, P, one of which has its edge P' bent into a head 85 to form a stiff extremity to the rib and closing over the edge of the other side to form a finished structure adapted to maintain its shape in installation and use. The pliable ledges in this form comprising sections 90 O, O have their double bend closed tight, so that with the suitable thickness of pliable metal the two portions of the bend can be distorted without distorting the rib or stiff portions of the bar or came to in 95 any material way affect the uniformity of the structure after repair or after the original assembly of the sectional bend.

As shown in Figs. 6 and 7, the pliable ledge G shown in dotted lines in distorted 100 position G' may be serrated as shown in the elevation, Fig. 6, so that each section can be bent up and back into clamping position with more facility and evenness. As so made, the many edges of a serrated pliable 105 ledge provide additional holding crevices for putty which is later applied to finish the job. These sectional or serrated portions of the pliable ledge on the glazing bar may be of many forms and may be in the form 110 of a few prongs or may constitute half or more of the length of the ledge. Being integrally formed with the sheet metal, they are readily made and form a strong and permanent means of attachment of the edge 115 of the glass and may be bent in and out for purposes of repair to any extent that may be required in usual or in extreme cases where the facilities for replacement or repair are required.

It will thus be seen that the side frame and the sash or window pane can be secured at one corner and an adjacent section of glass pushed into position snugly fitting into the pocket formed by the fixed edge and the pliable edge and an improved bar or came is then placed over the other edge of the glass section and on its opposite side the next piece of glass is inserted, with a further section of the glazing bar placed 125 130

in position, until all sections of bar and glass are in their proper position, and during the operation this improved glazing bar provides for securely holding the sections, 5 thereby greatly facilitating the assembly of leaded panes or the operation of assembling Gothic window glazing and minimizes the chance of breakage and assures protection in producing the finished pane or window. When all parts have been assembled, the corners and joints of the metallic side members and intermediate glazing bars are connected by soldering in the usual way or as may be otherwise desired.

15 In the case of breakage, the splinters are removed from the broken section and the pliable ledge quickly bent back to clear the edge of a new piece of glass which is inserted without straining the glazing bar 20 or frame or without distorting and marring the finish and appearance of the ribs or bars, and when inserted the pliable ledge is bent into holding position and, where desired, the putty finish is added, completing 25 the operation with great economy and perfection. In form shown, as for example, in Fig. 5, the securing can be effected leaving the pane in perfectly finished condition without the addition of putty, while 30 still providing a finished and neat appearance, both air-tight and without objectionable crevices for the accumulation of dirt and without leaving any ragged edges to the came or bar.

35 The various sections of glazing bar can be readily drawn from sheet metal of any desired thickness necessary to provide rigidity and still leave pliable the ledge or ledges which it is desired to distort for purposes 40 heretofore set forth.

The folds of the metal constituting a rib on one side may be so arranged as to permit the insertion of a straight or other suitable strip of metal when the glazing bars 45 have been assembled or when the window has been completely assembled, thereby providing a stiffening of the structure. This may be a steel strip which would provide strength far beyond the pliable or soft zinc 50 sheet used to readily form a manifolded special section. The hollow rib on one side may likewise accommodate a stiffener bar, as, for example, a steel rod; thus, the steel rods or bars let into or passed into the glazing bars of special conformation heretofore 55 described, serve to give great rigidity to the window and may furthermore be interlocked to increase the structural advantage. Such bars may also serve by insertion to spread 60 the parts of the pliable came or glazing bar after the glass has been positioned, thereby taking up any slack in the pockets which might exist owing to clearance necessary for its original insertion. Such bars or rods 65 may be varied by insertion of sections, par-

ticularly at the joints of the glazing bars, and by interlocking the same by perforations in one member, penetrated by the bar passing through the transverse member, or in many other ways.

70 By the use of the invention heretofore described, it will, thus, be seen that this glazing bar involves a weatherproof structure, all seams being covered or blind, none being exposed to permit the entrance of the 75 elements, which likewise applies when the stiffening bars are inserted inside of the specially formed glazing bar, thus preserving a durable and uniformly lasting exterior, irrespective of any possible rusting that 80 might be involved in the use of steel or other interior metal, which however is protected against the weather.

85 The various forms of this article of manufacture in its main features involve the sheet metal strip with the different ledges, legs and ribs formed by drawing it through a die but with such ledges or legs and pliable beadings integral with the main portion of the structure.

90 The resulting article of manufacture lends itself to various modifications based on engineering considerations and, in particular, in conformation to all the artistic requirements of windows of the class for 95 which this is intended.

95 With respect to the question of fire resistance, the weakening or partial destruction of zinc or other metals having a low melting temperature, it will be seen that the 100 supplementing or modification by adding the interior bars or rods, permits the use of steel of relatively great heat resistance, thereby providing a window that will withstand the effects of fire to a far greater extent, besides providing the strengthening 105 heretofore mentioned, to resist greater wind pressures.

110 While my invention may be variously modified from the particular embodiments herein described in detail and illustrated in the accompanying drawings, without departing from my invention, what I claim and desire to secure by Letters Patent is:

115 1. A glazing bar comprising a continuous strip of metal having a lateral pocket adapted to receive and hold a sheet glass edge, a stiff rib formed as part of the one piece strip by a bend on one side, a fixed ledge forming one side of said pocket and a pliable ledge of the integral metal strip forming a yielding, complementary side to said pocket.

120 2. A glazing bar consisting of a strip of metal with continuous bends having a pocket on one side to accommodate the edge of a piece of glass, a fixed ledge forming one side of said pocket in combination with an integral stiff rib bent portion, an edge of said metallic strip constituting a pliable ledge on the opposite side of said pocket.

3. A glazing bar consisting of strip of sheet metal and drawn into a section forming a stiff rib, stiff integral ledges adjacent said rib and a bent section forming an oppositely disposed stiff rib and a return bend from said second rib terminating in a pliable glass-holding ledge at the edge of the strip.
4. A glazing bar comprising a strip of sheet metal having a pocket formed by a groove bend on one side and having a stiffening rib projecting from the opposite side of said pocket, a pliable section on one side of said pocket formed by the edge of the strip adapted to be bent for the purpose described.
5. A glazing bar comprising a sheet metal strip drawn to a uniform section, consisting of a stiff wide rib on one side and a stiff narrow rib projecting in the opposite direction, two laterally disposed intermediate bends forming a pliable ledge adapted to form a pocket in conjunction with a base ledge on one of said stiffening ribs.
6. A glazing bar comprising sheet metal strip drawn into continuous uniform section having a stiff rib section on one side with a base thereof to form a fixed ledge or pocket side, a pliable ledge formed from the edge of the sheet in serrations, sections of said serrations integral with the metal sheet, individually pliable and independent of each other.
7. In a window having a sub-divided sectional pane, a sash rail of continuous uniform section of single-piece drawn sheet metal, intermediate glazing bars of single-piece uniform section integral sheet metal, including a strip portion of said sheet metal formed on the rails and bars with a pliable juncture with the main body portion whereby the same are pliable and may be opened to permit the insertion of the glass edge and rebent to hold the same in position.
8. An article of manufacture consisting of a deformable metal sheet drawn to a uniform section of folds including in the integral continuity of the structure a stiff box rib section, a permanent ledge to accommodate an abutting edge of a glass plate, and an integral portion pliable with respect to the structure along a line close to the axial plane of the glazing bar, whereby said section may be bent to and over to hold said glass plate in co-operation with the permanent ledge.
9. An article of manufacture, a glazing bar with portions formed of integral uniform sheet metal section including a rib bend forming a rib section with the sides brought adjacent to each other to form an abutment for the juxtaposed glass pieces, and a strip projecting from the adjacent parts to form a pliable beading and a bent part forming a closure for the space intermediate the adjacent members, whereby a finished and weatherproofed joint is formed on the portions extending in the opposite direction from the rigid rib.
10. A glazing bar consisting of a single strip of sheet metal formed into a section comprising a pocket to receive the edge of a glass plate with a ledge abutting one side of said glass edge, an integral stiffening rib disposed at right angles to said ledge, and a terminal edge of said sheet metal strip laterally projecting from said stiffening rib to form the complementary pocket side.
11. A glazing bar consisting of a drawn strip of sheet metal the longitudinal bends of which strip are formed to constitute a section with a head, a stiff rib disposed at right angle to said head, a terminal strip edge of said strip laterally projecting from said stiff rib forming with the head a pocket for the edge of a glass plate.
12. A T section glazing bar comprising head and web formed of a continuous strip of pliable sheet metal, a single ply of said strip projecting from said web intermediate the head and the outer edge of the web and forming a lip parallel with said head.
13. A T-shaped glazing bar comprising head and web formed of a continuous strip of pliable sheet metal, a ply of said strip bent back from the edge of said web with an integral portion projecting laterally from said web and forming a pocket in conjunction with the head.
14. A window came or bar of one piece of sheet metal comprising a head and a bent forming a stiff rib and a contiguous pliable edge of single thickness of said sheet metal projecting at right angles intermediate the head and web edge, said rib serving to hold the edge of a glass pane.
15. A window came consisting of a one piece sheet metal strip bent to T-shape section forming a stiff web and a stiff head, and a pliable sheet edge projecting laterally from said stiff web substantially medial of the side of the web.
- In testimony whereof, I have signed my name to this application, in the presence of two subscribing witnesses, this 6th day of May, 1921.
